UNITED STATES PATENT OFFICE.

ALBERT S. JANIN, OF NEW YORK, N. Y.

TILE.

No. 909,603.

Specification of Letters Patent.

Patented Jan. 12, 1909.

Application filed March 11, 1908. Serial No. 420,398.

To all whom it may concern:

Be it known that I, ALBERT S. JANIN, a citizen of the United States, and a resident of the city of New York, Rosebank, borough 5 of Richmond, in the county of Richmond and State of New York, have invented a new and Improved Tile, of which the following is a full, clear, and exact description.

The invention relates to tiles for walls, 10 floors and similar purposes, and its object is to provide a new and improved tile having a symmetrically curved outline arranged in such a manner that similar tiles can be readily interlocked to prevent displacement in 15 any direction and to present a highly ornamental surface.

The invention consists of novel features and parts and combinations of the same, which will be more fully described herein- 20 after and then pointed out in the claims.

A practical embodiment of the invention is represented in the accompanying drawings forming a part of this specification, in which similar characters of reference indicate 25 corresponding parts in all the views.

Figure 1 is a plan view of a series of interlocked tiles colored differently; Fig. 2 is a like view of a series of interlocked tiles colored differently; and Fig. 3 is a perspective 30 view of a single tile.

The tiles A to be interlocked with each other are exactly alike in shape and size, each tile being approximately of a square shape, having a center or a body A' and 35 sides, each of which is formed with a hooked tongue A² and a recess A³, the recess A³ and the tongue A² being of exactly the same size and shape, the only difference being that the recess A³ is reverse to the tongue A². The 40 tongue A² is in the form of a hook, and the terminal of the tongue defines the hook end of the recess A³, and by reference to the drawings it will be seen that the tongue and recess are contiguous, and the tongues and 45 recesses along the entire margin of the tile alternate. Now by the arrangement described, the tongue A² of one tile readily interlocks with the recess A³ of an adjacent tile, and by having the tongues and recesses

arranged as described, an entirely unbroken 50 surface is provided when interlocking a series of tiles as above described and shown in Figs. 1 and 2.

It will be noticed that when the tiles are interlocked they are held against movement 55 in any direction in the plane of the tiles, and consequently the tiles are not liable to come apart when once laid in position on the floor, wall or other structure. Each tile in itself is ornamental in configuration, and 60 by constructing a tile as described, they can be readily interlocked to form say different centers, especially when using different colored tiles; for instance, as shown in Fig. 1, four tiles of the same color are inter- 65 locked to form the center, while the outer tiles interlocked with the said center tiles are of a different color, and consequently a wide contrast is had. As illustrated in Fig. 2, five tiles of one color are interlocked to 70 form a center which is in contrast to the outer tiles interlocked with the said center tiles.

The tile may be made of any suitable material such as rubber, clay, porcelain and 75 the like, but in each case the tiles are alike in size and shape, and each side is formed of a hooked tongue and a contiguous recess, as above described and shown in the drawings.

Having thus described my invention, I 80 claim as new and desire to secure by Letters Patent:—

1. A tile having sides, each formed of a hook-shaped tongue, and a hook-shaped recess complementary to the said tongue in shape and size, the hook extending outward and the recess inward, the terminal of the hook of the tongue defining the hook portion of the recess the tongue and the recess 90 occupying the entire extent of the side.

2. A tile having sides each formed of a hook-shaped tongue, and a hook-shaped recess complementary to the said tongue in shape and size, the hook extending outward 95 and the recess inward, the terminal of the hook of the tongue defining the hook portion of the recess, and the outer edge of the

tongue conforming to the back of the recess the tongue and the recess occupying the entire extent of the side.

3. A tile having sides each formed of a hook-shaped tongue and a hook-shaped recess complementary to the said tongue in shape and size, the hook extending outward and the recess inward, the terminal of the hook of the tongue defining the hook portion 10 of the recess, the tongues and recesses alter-

nating along the entire margin of the tile the tongue and the recess occupying the entire extent of the side.

In testimony whereof I have signed my name to this specification in the presence of 15 two subscribing witnesses.

ALBERT S. JANIN.
